Primary Examiner — Catherine Ho(74) *Attorney, Agent, or Firm* — Sughrue Mion, PLLC(57) **CLAIM**

I claim the ornamental design for an aluminum shelf label holder, as shown and described.

DESCRIPTION

FIG. 1 is a front view of an aluminum shelf label holder showing my new design;

FIG. 2 is a left back perspective view thereof;

FIG. 3 is a front left perspective view thereof;

FIG. 4 is a top left perspective view thereof;

FIG. 5 is a right side elevation view thereof; and,

FIG. 6 is a top plan view thereof.
